[57] CLAIM

The ornamental design for a flat panel display with a tilt and swivel base, as shown and described.

DESCRIPTION

FIG. 1 is a front elevational view of a flat panel display with a tilt swivel base showing my new design;
FIG. 2 is a right front perspective view thereof;
FIG. 3 is a left front perspective view thereof;
FIG. 4 is a rear elevational view thereof;
FIG. 5 is a left rear perspective view thereof;
FIG. 6 is a right rear perspective view thereof;
FIG. 7 is a right side elevational view thereof;
FIG. 8 is a left side elevational view thereof;
FIG. 9 is a left front perspective view of a second embodiment of my new design; and,
FIG. 10 is a right front perspective view thereof.

FIG. 1

FIG. 2

FIG. 3
